Patented Sept. 1, 1925.

UNITED STATES PATENT OFFICE.

WERDON H. ALLEN, OF SOUTH MONTROSE, PENNSYLVANIA.

HANGER.

Application filed March 25, 1922. Serial No. 546,803.

To all whom it may concern:

Be it known that I, WERDON H. ALLEN, a citizen of the United States, residing at South Montrose, in the county of Susquehanna and State of Pennsylvania, have invented new and useful Improvements in Hangers, of which the following is a specification.

This invention relates to garment hangers primarily designed for use with wardrobe trunks and contemplates a construction which affords the device maximum strength and rigidity to prevent of its being extended or easily broken.

More specifically stated, use is made of a wooden member which is associated with one or more parts of the hanger and arranged with its grain disposed obliquely or at a right angle to the grain of the member or members of the hanger with which it is used, and when used in combination with several members of a single article, it serves to join said members together.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view in elevation and partly in section of one form of the invention.

Figure 2 is a similar view.

Figure 3 is a perspective view of the adjacent ends of certain parts of the device as illustrated in Figures 1 and 2.

Figure 4 is a sectional view taken on line 4—4 of Figure 1.

Figure 5 is a sectional view taken on line 5—5 of Figure 1.

Figure 6 is a view similar to Figure 1, of a modified construction.

Figure 7 is an elevation of the device illustrated in Figure 6.

Figure 8 is a sectional view taken on line 8—8 of Figure 6.

Figure 9 is a fragmentary view, partly in section of a modified construction.

Figure 10 is a view in elevation, partly in section of a further modified construction.

Figure 11 is an edge elevation of the device illustrated in Figure 10.

Figure 12 is a view in elevation, partly in section of a still further modified construction.

Figure 13 is a fragmentary view partly in section of another modified form.

Referring to the drawings in detail, and particularly to Figures 1 and 2, I have illustrated a garment hanger which includes a cross bar 10 which terminates to provide hook-like extremities 11 to permit of its use in conjunction with a wardrobe trunk or the like. In this form of the invention, the frame indicated generally at A is of substantially D-shape, and includes the members 12, 13 and 14, the latter being extended from the terminal of the member 12 to the corresponding terminal of the member 13. The member 12 has its upper end grooved as at 15 to receive the tongue 16

projecting from the meeting end of the member 13, while rising from the adjacent ends of these members are extensions 17 which are brought into face to face contact when the members are associated. Each of the extensions 17 is formed with an inclined surface 18, the latter of the member 13 merging into a flat surface 19 as illustrated in Figure 3. When the members 12 and 13 are associated by the tongue and groove connection, the extensions 17 of the respective members unitedly define what may be termed a tongue which is received by a groove 20 formed in the cross member 10, this groove opening at the lower edge of this member and of sufficient dimensions to snugly receive the tongue just referred to.

Each hook-like extremity 11 is kerfed as at 21, as is also the opposed ends of the member 14 as indicated at 22. When these parts are associated or arranged relatively in the manner shown in Figure 1, wooden members 23 are wedged into the kerfs 21 and 22, serving as a joint to hold the member 14 fixed relatively to the members 12 and 13. As illustrated, the grain of the members 23 is arranged either obliquely to

or at right angles to the grain of the members 12, 13 and 14 so as to afford the hanger at these points maximum strength and rigidity, with a view of preventing them from being warped or easily broken. The joint between the members 12 and 13 and the member 10 cooperates with the members 23 for this purpose. It will be noted that

the construction illustrated in Figure 2 is identical with that shown in Figure 1, ex-

cept that in Figure 1 it is made of the member 14 which is of course eliminated in the device shown in Figure 2.

In Figures 6 and 7, I have illustrated a modified form of the invention, wherein the hanger includes an upper member 24 and a lower member 25, these members being connected together by the member 26. The member 24 terminates to provide a hook like extremity 27 for the purpose above mentioned in connection with the structure shown in Figure 1, and each of these extremities kerfed to accommodate the wooden member 28. The member 28 is arranged with its grain arranged obliquely or at right angles to the grain of the member 24 for the purpose above mentioned. The member 25 is made in two sections, one of which is provided with a groove 29 and the other with a tongue 30, the parts being joined together in a manner illustrated in Figure 7. The opposed ends of the member 26 are grooved as at 31 to receive a portion of a filler or connecting member 32, and these members provide a joint between the member 26 and the members 24 and 25 respectively.

A portion of the member 32 projects from the upper end of the member 26 and is received by a groove 33 formed in the lower edge of the member 24, while a portion of the member 32 projecting from the lower end of the member 26 is received by a groove 34 formed in the member 25 at the tongue and groove connection between the respective sections of said member 25. Each member 32 has its grain arranged obliquely to the grain of the members with which they are associated, thereby rendering the structure in its entirety very strong. In Figure 9, I have shown a fragmentary view of a further modified form of the invention which is intended to be of the same configuration as the device shown in Figure 6, but in this form of the invention, the member 35 is associated with the member 36 by means of a tongue 39 which is an integral part of the member 36. In other words, the member 35 is made in two sections, one of which is formed with a groove 37 and the other with a tongue 38, the latter being fitted in the groove 37 as shown. The member 35 is grooved as at 40 to receive the tongue 39 of the member 36.

In Figure 10, I have illustrated another modified form of the invention wherein the hanger proper includes the members 41 and 42, the outer ends of which are joined by the members 43. The members 41 and 42 have their upper ends joined together by a tongue

and groove connection with the tongue 44 arranged obliquely to the adjacent end of the member 41. The outer ends of the members 41 and 42 are kerfed as is also the opposite end of the member 43 to receive the member 45 which is disposed with its grain arranged obliquely to the grain of the members with which they are associated.

In Figure 12, I have shown another modification, wherein the hanger is made up of the members 46, 47, and 48, this form of the invention having the same configuration as the device shown in Figure 10. The corresponding outer ends of the members 46 and 47 are kerfed as is also the opposed ends of the member 48 to receive the member 49 which is similar in construction and arranged in the same manner as the member 45 described in connection with Figure 10. However, this form of the invention varies from the showing in Figure 10, in that the tongue and groove connection between the meeting ends of the members 46 and 47 is such that the tongue is arranged perpendicularly in contra-distinction to the showing of the tongue 44 in Figure 10.

In Figure 13, I have illustrated another modified form of the invention which is intended to have an outline similar to the device illustrated in Figure 10, but differentiating from the latter mentioned figure, in that the member 50 is terminally connected with the member 51 by grooving the member 50 as at 52 to receive the reduced extremity 53 of the member 51. This construction is in contra-distinction to that illustrated in Figure 10, wherein the corresponding members are both slotted or grooved and joined by the element 45.

What I claim is:

A combined coat and trousers hanger comprising a bar provided with a recess in the center face, a pair of divergent arms formed with relatively large extensions upon their inner ends, one of such ends being provided with a groove, a tongue projecting from the other of such ends and received in the groove, beveled extensions formed on the enlarged ends and wedged into the recess in the bar, a cross bar for supporting a pair of trousers arranged beneath the outer ends of the arms, the outer ends of the arms and bars being provided with kerfs, and substantially semi-circular locking elements arranged in the kerfs and having their curved edges contiguous with the upper face of the arms.

In testimony whereof I affix my signature.

WERDON H. ALLEN.
